(57) **CLAIM**

The ornamental design for a switch paddle for a mountable light, as shown and described.

DESCRIPTION

FIG. 1 is a top isometric view of a first embodiment of a switch paddle for a mountable light, showing my new design;

FIG. 2 is a bottom isometric view of the switch paddle for a mountable light shown in FIG. 1;

FIG. 3 is a front elevational view of the switch paddle for a mountable light shown in FIG. 1;

FIG. 4 is a right side elevational view of the switch paddle for a mountable light shown in FIG. 1;

FIG. 5 is a rear elevational view of the switch paddle for a mountable light shown in FIG. 1;

FIG. 6 is a left side elevational view of the switch paddle for a mountable light shown in FIG. 1;

FIG. 7 is a top plan view of the switch paddle for a mountable light shown in FIG. 1;

FIG. 8 is a bottom plan view of the switch paddle for a mountable light shown in FIG. 1;

FIG. 9 is a top isometric view of a second embodiment of a switch paddle for a mountable light, showing my new design;

FIG. 10 is a bottom isometric view of the switch paddle for a mountable light shown in FIG. 9;

FIG. 11 is a front elevational view of the switch paddle for a mountable light shown in FIG. 9;

FIG. 12 is a right side elevational view of the switch paddle for a mountable light shown in FIG. 9;

FIG. 13 is a rear elevational view of the switch paddle for a mountable light shown in FIG. 9;

FIG. 14 is a left side elevational view of the switch paddle for a mountable light shown in FIG. 9;

FIG. 15 is a top plan view of the switch paddle for a mountable light shown in FIG. 9; and,

FIG. 16 is a bottom plan view of the switch paddle for a mountable light shown in FIG. 9.

(Continued)

The broken lines represent portions of the switch paddle for a mountable light that form no part of the claimed design.
